UNITED STATES PATENT OFFICE.

WILLIAM MENGE, JR., OF DOLGEVILLE, NEW YORK, ASSIGNOR TO DOLGEVILLE FELT SHOE COMPANY, OF DOLGEVILLE, NEW YORK, A CORPORATION OF NEW YORK.

MANUFACTURE OF SHOES.

1,142,265.

Specification of Letters Patent. Patented June 8, 1915.

Application filed February 21, 1914. Serial No. 820,211.

To all whom it may concern:

Be it known that I, WILLIAM MENGE, Jr., a citizen of the United States, and a resident of Dolgeville, county of Herkimer, 5 and State of New York, have invented a certain new and useful Improvement in the Manufacture of Shoes, of which the following is a full, clear, and exact specification.

This invention relates to shoes, more particularly to the manufacture thereof, and consists in the devising of a novel way of constructing a composite sole for light wear shoes and slippers, and of sewing, or otherwise securing together, of such sole, insole 15 and of the upper of the shoe in one operation.

A composite sole, and a shoe, constructed according to my invention, are illustrated in the accompanying drawings, wherein—
20 Figure 1 is a plan view of the outer sole and of the filling, laid thereon. Fig. 2 is a longitudinal sectional view thereof on line 2—2 indicated in Fig. 1. Fig. 3 is a similar view to Fig. 2 but showing also the 25 insole, laid over the filling, and the outer sole, and temporarily secured thereto. Fig. 4 is a longitudinal sectional view of a shoe, showing the upper and the composite sole, permanently secured together, this figure 30 showing the parts of the shoe in the position before the shoe is turned. Fig. 5 is a view similar to Fig. 4 but showing the relative positions of the parts after the shoe is turned and lasted.

35 The outer sole, designated *a* in the drawings, is preferably cut of flexible leather, of sheepskin or the like, though other material, as for instance, rubberized canvas and the like may be used. If cut of sheep-
40 skin or other similarly pliable material, a layer *a'* of felt, or of thick cotton fabric may be cemented to the surface of the outer sole, whereon the filling *d* is laid. The sole *a* is cut larger than the size of the shoe, for
45 which it is to be used, to provide a circumferential margin *c* for the joining of the insole thereto, and of the sole and insole to the upper. The insole may be made of felt or other suitable fabric, or of soft
50 leather. The upper may be of any desired shape. It is usually cut in one piece, the front end forming the vamp, and the sides and heel part extending therefrom so that by sewing the ends of the extensions together, the upper is completed. The filling
55

d may be of any desired or suitable material—soft or heat insulating, like carded wool or cotton batting; it is cut in a shape corresponding to that of the bottom of the last, its size, however, is slightly less than 60 the size of the last, whereon the shoe is to be lasted; it is best to cut the filling so there will be a free margin of about, or not more than, one eighth of an inch around, if placed upon the bottom of the last. 65

When constructing the shoe, the filling *d* is placed upon the outer sole—upon the surface, whereon the insole *f* comes to lie—equi-distantly from the edges thereof; it may be lightly attached thereto, just sufficiently to keep it in its place while the insole is laid thereon, and while the sewing together of the edges of the insole of the outer sole, and of the upper *e* is done. 70 Then the insole is laid thereon and the 75 edges of the sole and of the insole pressed, or may be cemented, together. Next the sewing together of the upper and of the composite sole is done. This is done preferably while the parts of the shoe are 80 turned wrong side out, the upper having been previously sewed together as explained. Then the sewed edge is neatly trimmed, the shoe turned and lasted.

By this method of manufacture a saving 85 of labor and of handling is effected, the sewing on of the insole upon the outer sole, which must be done by hand, and also the attaching of the filling thereto, if the shoe is to have a padded sole, being dispensed 90 with. Furthermore, by following the method herein set forth, a shoe neater in appearance, and more durable is produced, than can be produced by the methods heretofore known. The insole adds substance to 95 the strength of the seam, and being thus secured in its place, by stitching located beyond the reach of the foot of the wearer, it is held in its place as long as the shoe lasts, its edges are not frayed or the stitching 100 worn out as it now happens.

The improvement is particularly advantageous in the manufacture of the so-called "soft sole" and "padded sole" shoes and slippers, but may also be advantageously 105 employed in the manufacture of other kind of shoes, where insoles of any special kind or for particular purposes are used.

I claim as my invention:
The method of making a turned slipper 110

comprising an upper, an outer sole, an inner sole and a filler of carded material between them, marginally spaced from the edges of the inner and outer soles, consisting in placing such filler between the inner and the outer soles free from attachment thereto, then sewing together, in a single operation, the adjacent edges of the upper

and of the inner and outer soles, and finally turning and lasting the slipper; substantially as herein shown and described. 10

WILLIAM MENGE, JR.
